SPEAKER CABINET

Alfred J. Erickson, 928 S. Hampstead St.,
Anaheim, Calif.

Filed Oct. 25, 1962, Ser. No. 72,269

Term of patent 14 years

(Cl. D26—14)

FIGURE 1 is a front perspective view of a speaker cabinet, showing my new design;

FIGURE 2 is a front elevational view, to a reduced scale, the rear being substantially a mirror image thereof;

FIGURE 3 is a top plan view; and

FIGURE 4 is an end elevational view, the opposite end being substantially a mirror image thereof.

The side not shown is a mirror image of the side shown.

The dominant features of the design reside in the portions shown in full lines.

I claim:

The ornamental design for a speaker cabinet, substantially as shown and described.
